UNITED STATES PATENT OFFICE.

REINHOLD BRÄUER, OF DUSSELDORF, GERMANY.

SAFE.

Application filed June 10, 1922. Serial No. 967,501.

To all whom it may concern:

Be it known that I, REINHOLD BRÄUER, a citizen of the German Republic, residing at Dusseldorf, Germany, have invented certain 5 Improvements in Safes, of which the following is a specification.

To prevent safes from being carried away it is necessary that they should be of considerable weight. It is also essential that 10 they should be made fireproof and capable of resisting attacks by breaking and fusing tools. They are therefore generally costly and difficult to transport from place to place. To overcome the difficulties of transport, 15 safes are sometimes constructed out of detachable blocks which are assembled in situ and connected by internal elements which are inaccessible when the safe is closed.

The invention relates to a safe of this kind 20 and consists in forming the body of the safe out of a plurality of nested frames which are clamped together between a front frame and a rear wall.

A safe constructed in this manner will, 25 while being easy to transport and to erect, ensure the same degree of safety as those constituting an integral structure.

In the accompanying drawings

Fig. 1 represents a vertical section of a 30 safe having a single compartment,

Fig. 2, a horizontal section of the same,

Fig. 3, a vertical section showing a combination of two superposed safe-compartments,

Fig. 4, a vertical section at right angles to 35 Fig. 3,

Fig. 5, a horizontal section of Fig. 3, and

Fig. 6, a front view of the entire structure.

Fig. 7 is a vertical section showing a combination of two safe compartments arranged in juxtaposition, and

Fig. 8, a front view of the same.

Figs. 9 and 10 are corresponding views showing a combination of four safe-compartments.

Fig. 11 is a horizontal section of this arrangement, and

Fig. 12, a top view of the same.

Fig. 13 is a front view showing how any 50 number of safes can be combined in juxtaposition.

The back wall of the safe is composed of a slab *a* which may be made of concrete and suitably reinforced. Anchored to the reinforcements are screw-bolts *i* which project into the interior of the safe and serve as

means for securing the various parts together. The rest of the safe is built up, to any desired depth, by external blocks in the form of rings or frames *c*, and by internal frames or slabs *b*, all appropriately reinforced. There may be several sets of nested or overlapping blocks *b*, dependent on the desired degree of strength, and the joints of these blocks are staggered relative to each other and to the joints of the blocks *c* so that no access to the interior of the safe is possible. The outer margins of the slab *a* are reduced so as to form a shoulder for holding the other blocks in position. The structure is terminated by a front frame *d* which overlaps the blocks *c* and *b* and which is recessed to receive a metal frame *g* and with it the door *h* of the safe. The frame *g* is connected either to a complete box *f* which fills up the interior of the safe, or merely to straps which, like the box, can be secured by means of nuts and by means of a clamping plate *e* to the bolts *i*. The nuts can be tightened up for forcing the frame *g* to the block or frame *d* and the latter to the blocks *b* and *c*. Thus a firm structure is obtained which cannot be taken to pieces without access to the bolts *i* from the interior of the safe. If the individual blocks are made up so as to require two men or the full strength of a single man to handle, the complete safe will be able to defy removal. The door *h* is preferably composed of a concrete-filled steel frame and is fitted with the usual locking arrangement.

The different parts of the safe can be made up in standard sizes, and the number of parts employed in any particular safe can be varied in accordance with the desired depth of the safe. Thus, apart from the ease with which the safe can be erected and removed, a considerable reduction in the cost of manufacture will be achieved. The fastening elements, being enclosed within the safe, will be protected from fire as well as from breaking attacks. The rings or frames *c* may be replaced by plates adapted to interlock so as to be inseparable until the internal fastening is removed.

Several safes or compartments may be combined into one structure, as shown in Figs. 3 to 11. The back slab *a* is in each case modified to accommodate the different cross-walls formed by the blocks *b*. The blocks *c* embrace the entire structure, and each safe or compartment is fitted with in-

dependent fastening elements, so that all the doors must be opened before the parts can be separated.

In the structure according to Figs. 3 to 6 5 two safes are arranged in this manner one above the other. Figs. 7 and 8 show them arranged side by side, and Figs. 9 to 12 show how four safes may be combined in the manner just described. The safes may be 10 arranged with the plates *a* and the doors in a horizontal instead of a vertical position, and they may be built into walls if desired.

The safe may be concealed by means of 15 an ordinary piece of furniture made so as to fit over it.

A group of independent safes may be arranged in juxtaposition, as shown in Fig. 13, and interconnected by means of screw-bolts or other elements passing from the 20 interior of one safe to that of the next. In this arrangement new safes may be added to the group in proportion as required.

I claim:—

1. A safe composed of detachable blocks 25 of masonry and having a rear wall in the form of a slab, a series of nested frames abutting against a recessed part of the slab and forming the side and the end wall, a front frame overlapping the nested frames, 30 and means for clamping the parts together between the slab and the front frame, such clamping means being arranged inside the

safe, substantially as and for the purpose set forth.

2. In a safe formed of detachable blocks 35 of reinforced concrete, a rear wall in the form of a slab, a series of nested frames abutting against the recessed part of the slab and forming the side and the end walls, a front frame overlapping the nested frames, a door frame recessed into said front frame, and means for connecting said door frame to the slab so as to clamp the nested frames between the front frame and the slab, such clamping means being arranged inside the safe, substantially as and 40 for the purpose set forth.

3. In a safe formed of detachable blocks 45 of reinforced concrete, a rear wall in the form of a slab, a series of nested frames 50 abutting against a recessed part of the slab and forming the side and the end walls, a front frame overlapping the nested frames, a metal box fitted within the nested frame, a door frame integral with the metal box 55 and recessed into said front frame, and screw-bolts connecting said box with the slab so as to lock the frame in position by the engagement of the door frame with the front frame, said screw-bolts being concealed within the box, substantially as and 60 for the purpose set forth.

REINHOLD BRÄUER.
